UNITED STATES PATENT OFFICE.

MAURICE BALLIN, OF OAKLAND, CALIFORNIA, ASSIGNOR TO NEUSTADTER BROS., OF SAN FRANCISCO, CALIFORNIA, A CORPORATION OF CALIFORNIA.

ADJUSTABLE HEMMER.

1,254,875.

Specification of Letters Patent. Patented Jan. 29, 1918.

Application filed November 8, 1916. Serial No. 130,160.

To all whom it may concern:

Be it known that I, MAURICE BALLIN, a citizen of the United States, residing at Oakland, in the county of Alameda and State of California, have invented new and useful Improvements in Adjustable Hemmers, of which the following is a specification.

This invention relates to an adjustable hemmer for sewing machines.

In the sewing of factory made shirts, 20 waists, overalls and like wearing apparel, and particularly in sewing hems of varying widths on the same garment, it is common practice to resort to several operations as it is necessary to stop and change to different size hemmers as the work on the garment progresses. The several operations add considerable cost to the production and general output as it not only interferes with the time 25 of the operators, but also with the continuous operation of the machines.

The object of the present invention is to overcome the above named objections by providing an adjustable hemmer and particularly a hemmer which may be changed or adjusted while the machine is running at 30 full speed, in this manner eliminating the several operations previously required and the necessity of stopping to change to different size hems.

Further objects will hereinafter appear.

The invention consists of the parts and the construction and combination of parts as hereinafter more fully described and claimed, having reference to the accompanying drawings in which:—

Figure 1 is a side elevation partly broken away, of a sewing machine showing the application of the invention.

Fig. 2 is a detailed plan view of the adjustable hemmer and the connected mechanism whereby it is actuated.

Fig. 3 is a perspective view of the lower adjustable part of the hemmer.

Fig. 4 is a similar view of the upper stationary part of the hemmer.

Fig. 5 is a detailed perspective view showing the position of the adjustable hemmer with relation to the presser foot and needle bar.

Fig. 6 is a front view of a part of a garment showing different widths of hems that may be produced by an adjustable hemmer.

Fig. 7 is a side elevation of the connection

formed between the lever 11 and the presser 55 foot.

Fig. 8 is an end view of same, partly in section.

Referring to the drawings in detail, A indicates a bed plate on a sewing machine, 60 and 2 the upper frame or arm which carries the needle bar 3, and the presser foot 4, with connected operating mechanism. Pivotedly mounted below the bed plate A at any suitable point, is a rock shaft 5 on which is 65 mounted a knee lever 6 and a knee plate 7. The upper end of the knee lever is bent to form a cam 8 which is so positioned as to raise or lower a rocker arm 9 when the knee lever is swung with the rocker shaft. 70

Pivotedly mounted on one side of the main frame or arm 2 as at 10, is a lifting lever 11, one end of which is connected with the presser foot 4 in the usual manner, while the opposite end is connected to a lifting rod 12 75 and the rocker arm 9. The knee lever together with the rocker arm, the lifting rod and the lifting lever, form as a whole what is known as the knee lift, and while this mechanism is employed in conjunction with the adjustable hemmer forming the main subject matter of the present invention, I 80 wish it understood that it does not form any essential part thereof.

The adjustable hemmer consists of a stationary upper section 14 which is secured to and carried by a bracket plate 15 and a lower movable section 16 which is secured to and movable in unison with an arm 17. This arm consists of two sections 17 and 18 which are adjustably connected as at 19 to permit the arm as a whole to be shortened or lengthened as will hereinafter be described. The section 17 of the arm is slidably mounted in a bearing 20 formed on the bracket 95 plate 15, while the section 18 on the arm is pivotally connected as at 21 to a hook shaped rocker arm 22 which is pivotally mounted on the main bed plate A as at 23.

Suitably secured on the lifting rod 12 is 100 a cone shaped collar 24, and mounted on one side of the arm 22, adjacent the pivotal point 23, is an adjusting screw 25, by which movement of the arm 22 is restricted in one direction.

The knee lifting mechanism previously described, has heretofore been used solely for the purpose of lifting the presser foot 4 105

away from the feed bar and the throat plate when work is to be inserted. This mechanism has been utilized in the present instance for the purpose of operating the adjustable hemmer.

This is accomplished in the following manner:—If it is desired to sew a wide hem such as indicated at 29, see Fig. 6, when commencing a seam, it is only necessary to 10 press the knee lever 6 by means of the plate 7 into the dotted line position shown at 7^a. This movement is transmitted through the rocker arm 9, the lifting rod 12, and the lifting lever 11 to raise the presser foot away 15 from the throat plate and the feeding bar. The material to be hemmed or sewn is then inserted through the hemmer and under the presser foot to a point where the needle may engage. The knee plate is then slightly released to permit it to assume the dotted line position shown at 7^b, this movement is transmitted through the rocker arm and lifting rod to move the lifting rod to the dotted line position shown at 11^b. The cone shaped collar 24 will here assume the dotted line position indicated at 24^b or a point just below the hook shaped arm 22. This arm will then assume the dotted line position indicated at 22^b which is limited by the adjusting screw 25, the arm 22 being moved into this position by means of a coiled spring 30 surrounding the pivot 23, said spring having one end attached to the bed plate of the machine and the opposite end to the lever as indicated at 31. 30 This position of the arm 22 pulls the bar 17 together with the lower movable part of the hemmer, to a position where the greatest width of hem may be obtained, for instance a hem such as shown at 29, see Fig. 6. If 35 during the sewing operation it is desired to reduce the hem in width, it will only be necessary to release the knee plate 7 and permit it to assume the full line position shown. This allows the rocker arm to assume its full line position, and the cone collar 24 to assume the position where it will engage the inner hook shaped end of the arm 22, and swing it about the pivot to the full line position shown in Fig. 2. This 40 forces the bar 17 together with the lower part of the hemmer, forward in the direction of the arrow *a*, or to a point where a narrow hem will be produced such as indicated at 35, see Fig. 6. 45 The width of the hem may be increased or decreased by adjusting the length of the bar 17 by means of the adjusting screw 19, the extreme width of the hem being also secured by the same adjustment.

50 If it is desired to use the hemmer as an ordinary hemmer, and to render it inoperative when the knee lift is employed, it is only necessary to move the adjusting screw 25 to a point where it will hold the lever 22 55 out of engagement with the cone shaped

collar 24. It is therefore possible to render the hemmer inoperative when desired, or to permit it to be adjusted to make a wide or narrow hem, merely by rocking the knee lifting lever 6.

70

In many instances it becomes more than a hemmer, for instance on shirt work in the making of French fronts now so generally used by the shirt trade, it becomes possible to make a complete front, in this manner 75 saving three distinct operations which have heretofore been necessary, that is running, turning, and stitching. The present hemmer permits the making of any desired width of stitch on the center plait, see Fig. 80 6, and automatically reduces the said hemmer stitch to any degree of narrowness desired, this being done without even slowing down the machine, in other words, a change from a wide hem to a narrow hem can be 85 made while running the machine at full speed by simply moving the knee lift in one direction or the other, said movement as previously described being transmitted through the lifting rod and the cone shaped collar 90 24, which in turn actuates the bar 17 and the attached lower section of the hemmer. It is therefore possible to sew seams of varying widths while working on a single garment without stopping or resorting to other 95 operations, in this manner not only saving the time of the operator, but also permitting the machine to be operated continuously. A product of superior quality is not only produced, but the manufacturing cost is considerably less.

100

While the adjustable hemmer is here shown as being controlled and operated by the knee lift, it is obvious that a separate foot treadle or any other suitable mechanism may be employed for the purpose of shifting the movable part of the hemmer. Similarly the materials and finish of the several parts of the hemmer and attached operating mechanism may be such as the experience and judgment of the manufacturer may dictate.

105

By referring to Figs. 7 and 8, it will be seen that no movement is transmitted to raise the presser foot except when the knee lift is moved to the extreme position shown at 7^a. This is due to the fact that a pin 50, on the end of the lever 11, travels in a slotted bracket 51 which carries the presser foot, thereby preventing the presser foot from being lifted while the knee lift is moved from the full line position shown in Fig. 1 to the dotted line position shown at 7^b. The pin only engages and lifts the bracket when the upper end of the slot is reached or when the knee lift is moved to the extreme position shown at 7^a. Adjustment of the hemmer can, therefore, take place while the machine is operating and also without raising the presser foot.

115

Having thus described my invention, what 120 125 130

I claim and desire to secure by Letters Patent is--

1. The combination with the presser foot and the needle on a sewing machine of an adjustable hemmer adapted to form hems of varying widths positioned adjacent the presser foot, and means for adjusting the hemmer during the sewing operation to change the width of the hem during the 10 sewing operation.

2. The combination with the presser foot and the needle on a sewing machine of an adjustable hemmer adapted to form hems of varying widths positioned adjacent the 15 presser foot, a manually operated lever mounted on the sewing machine and means connecting said lever with the hemmer to permit adjustment of the hemmer and changing of the width of the hem while 20 sewing of the hem is taking place.

3. The combination with the presser foot and the needle on a sewing machine of a sectional hemmer mounted adjacent the presser foot, said hemmer comprising a stationary section and an adjustable section, and means for moving the adjustable section of the hemmer to adjust the width of the hem while sewing of the hem is taking place.

30 4. The combination with the presser foot and the needle on a sewing machine of means for raising the presser foot, an adjustable hemmer mounted adjacent the presser foot and means actuated by the 35 means for raising the presser foot for adjusting the hemmer to vary the width of the hem while sewing of the hem is taking place.

5. The combination with the presser foot 40 on a sewing machine and means for lifting same, of a hemmer mounted adjacent to the presser foot, said hemmer comprising a stationary section and a movable section, and means actuated by the foot-lifting means 45 for moving the movable section of the hemmer to increase or decrease the width of a hem.

6. The combination with a sewing machine and the knee lift connected therewith, 50 of an adjustable hemmer, and means actuated by the knee lift for adjusting the hemmer, said movement of the movable part of the hemmer being adapted to take place while the material to be hemmed is passing 55 through the hemmer and while the machine is sewing.

7. The combination with the presser foot 60 on a sewing machine and means for lifting same, of a hemmer mounted adjacent to the presser foot, said hemmer comprising a sta-

tionary section and a movable section, a 65 slidably mounted bar to which the movable hemmer section is attached, and means actuated by the foot-lifting means for imparting movement to the sliding bar and the attached hemmer section.

8. The combination with the presser foot on a sewing machine and the knee-lifting mechanism whereby it is lifted, of a hemmer 70 mounted adjacent to the presser foot, said hemmer comprising a stationary section and a movable section, a slidably mounted bar to which the movable hemmer section is secured, a pivotally mounted lever connected at one 75 end with the bar, and means actuated by the knee-lifting mechanism engageable with the opposite end of the pivotally mounted lever.

9. The combination with the presser foot and the needle on a sewing machine of an 80 adjustable hemmer mounted adjacent the presser foot and the needle, manually operated means for raising and lowering the presser foot and means connecting said means with the hemmer to permit adjustment thereof to change the width of the hem while sewing of the hem is taking place.

10. The combination with the presser foot and the needle on a sewing machine, of a 90 sectional hemmer mounted adjacent to the foot and the needle, said hemmer comprising a stationary section and a movable section, a lever pivotally mounted on the machine, and means connecting said lever with the movable section of the hemmer to permit 95 said movable section to be moved to adjust the width of the hem while sewing of the hem is taking place.

11. The combination with the presser foot and the needle on a sewing machine, of a 100 sectional hemmer mounted adjacent to the foot and the needle, said hemmer comprising a stationary section and a movable section, a knee-actuated lever pivotally mounted on the machine, a vertically positioned 105 rod adapted to be raised or lowered by the knee-actuated lever, a cam on the rod, a second lever pivotally mounted on the machine adapted to be engaged and rocked about its pivot by the cam, and a link connecting said lever with the movable section 110 of the hemmer.

In testimony whereof I have hereunto set my hand in the presence of two subscribing witnesses.
